UNITED STATES PATENT OFFICE.

DAVID HARRINGTON, OF WORCESTER, MASSACHUSETTS.

WATCH-PLATE.

SPECIFICATION forming part of Letters Patent No. 580,046, dated April 6, 1897.

Application filed July 12, 1895. Serial No. 555,708. (No model.)

To all whom it may concern:

Be it known that I, DAVID HARRINGTON, a citizen of the United States, residing at Worcester, in the county of Worcester and State of Massachusetts, have invented a new and useful Improvement in Chronometric Construction, of which the following is a specification.

The aim of this invention is to improve chronometric construction either in watch-work or in any train of similar gearing.

To this end the invention consists of the improvements herein described and more particularly pointed out in the claims appended to this specification.

My inventions are especially applicable to watch constructions; and to enable any person skilled in the art to which my improvements appertain to construct and use the same I will describe the same as applied to two of the ordinary forms of watches.

Referring to the accompanying three sheets of drawings, Figure 1 is a plan view of a watch-train with a cylinder-escapement with my improvements applied thereto. Fig. 2 is a similar view of a watch-train with a lever-escapement with my improvements applied thereto. Fig. 3 is a sectional view of the relief that I may use for the mainspring. Fig. 4 is a plan view of the base or plate which is used in the device shown in Fig. 2. Fig. 5 is a sectional view taken on the line 5 5 of Fig. 2. Figs. 6 to 11, inclusive, are detail views of the bridge that I preferably use to carry the balance-wheel. Figs. 12 and 13 are detail views of the bridge that I use to support the third, fourth, and fifth staves or shafts. Figs. 14 and 15 are similar views of a modification. Figs. 16, 17, and 18 are detail views of a further modification. Figs. 19 and 20 are detail views of the bridge that I preferably use to carry the barrel or mainspring. Figs. 21 and 22 are detail views of the bridge that I preferably use to carry the center staff; and Figs. 23 to 25, inclusive, are diagrammatic views illustrating the operation of adjusting one of the bridge-pieces that is preferably used for supporting either the third, fourth, or fifth staff.

My improvement relates to a novel way of mounting the staves which carry the gears and pinions. There are two ways now com-

monly practiced of mounting the bearings or jewels of the staves of a watch. The first is to arrange the jewels or bearings of each staff in two plates. The second way is to mount one of the jewels or bearings of each staff in a plate and the other jewel or bearing in a bridge-piece. The first arrangement, as described, permits of no adjustment between the staves, so that the gears and pinions can be properly meshed, or "depthened," as it is technically called. Neither does the same permit of any adjustment axially, so that the staff can be set to run properly or to adjust what is technically known as "end shake." In some watches made under the second construction the bridges may be set in various positions on the plate, but this only allows an adjustment of one of the bearings of each staff and does not insure the staves being kept in line. The common way of adjusting end shake in either of these constructions is to hammer, or "bump," as it is called in the art, either the plate or the bridge. This obviously is a "cut-and-try" method and depends upon the skill of the adjuster for its result.

The common way of "depthening" in watch-making, if adjustment is required, is to plug and then redepth. These methods of adjustment require adjusters who are exceedingly skilled in the art and such extremely accurate and nice machinery for so making the parts that when the watches are assembled little adjustment will be required. As distinguished from these old ways of making watches I mount the jewels or bearings of each staff of the watch that has two bearings in the two arms of a double bridge. Thus each staff with its gear and pinion or whatever the same carries can be placed in the bridge and these parts made in quantities. I preferably use for a plate a disk which is simply stamped out, and the bridges are so arranged that they can be set approximately on this disk, and then the gearing or train adjusted so as to get proper depthening, and then the arms of the bridges adjusted so that each staff will have proper end shake. This greatly simplifies and cheapens watch construction and watch adjustment.

The adjuster or setter-up of a watch made according to my inventions will have to sim-

ply put the bridges in place on the plate and then adjust the same to get the proper operation, and this adjustment can be effected in one form of my device by merely turning 5 screws. It will also be seen that my construction is very cheap, as the bearings or jewels and the various parts are very accessible as mounted in the bridges, and the parts can be assembled and the fittings largely completed before the watch is put together.

Referring now to the drawings, I will describe the specific construction which I have shown to illustrate the application of my inventions.

15 A represents the base or plate, which can be stamped out of metal and which may have the usual downwardly-extending flange *a* and the outwardly-extending flange *a'*, whereby the same can be inserted and held in the 20 watchcase in the usual manner.

B represents the barrel-wheel, C the center wheel, D the third wheel, E the fourth wheel, F the escapement-wheel, and G the balance-wheel, of any of the usual watch-trains. These gears C, D, E, and F are mounted 25 on the usual staves, which also carry the usual pinions by which the gears are meshed together in the well-understood manner.

In Fig. 1 I have shown my improvements 30 as applied to what is known as a "cylinder-escapement" in which the escapement-wheel meshes directly into a cylinder carried on the staff of the balance-wheel. In Fig. 2 I have shown my invention as applied to a lever-escapement in which a lever L is used between the escapement-wheel and the staff of 35 the balance-wheel. These parts are of the ordinary construction and require no detailed description.

40 The way I preferably mount and arrange the barrel-gear is as follows, and reference, to understand this description, should be had to the first sheet and to Figs. 19 and 20: The barrel-gear B carries the usual barrel 30, and these parts are mounted upon the usual staff 45 31, which carries the usual ratchet-wheel 32, engaging which is the usual pawl 33, controlled by a spring 34.

M represents the mainspring, which is arranged 50 in the barrel 30. One end of the mainspring is secured to the shaft 31 in the usual manner, and the other or free end of the mainspring is bent back upon itself and fits into the bent end 35 of the friction-spring 36, which is arranged in the barrel 30 and is coiled 55 in the same direction as the mainspring. The friction-spring 36 has sufficient friction or tension on the sides of the barrel 30 to allow the mainspring to be wound up in the usual 60 manner, either by key or stem, but when the mainspring is wound to the desired tension the friction-spring 36 will slip or turn in the barrel 30, thus preventing the mainspring from being broken or the parts from being 65 disarranged.

By coiling the friction-spring in the same direction as the mainspring it is to be noted

that the tension of the mainspring will tend to draw the friction-spring away from and out of engagement with the barrel, and as 70 the tension of the mainspring increases the pressure of the friction-spring upon the barrel, and hence its friction, will decrease.

b represents the bridge-piece in which I mount this barrel construction. This bridge 75 consists of a piece of metal which is bent to have a top arm 38, an end arm 39, and an under arm 40, and these arms 38 and 40 carry the bearings or jewels 380 and 400 for the staff 31. Also extending down from the top 80 arm 38 are side wings 41, which when the bridge is in place rest upon the base A and thus provide a strong box-like construction. The other end of the top arm 38 is bent down at the end, as at 42, under, as at 43, and is 85 provided with side arms 44, thus providing a similar box-like construction at the right-hand end of the bridge. Pins 45 are placed in the base-plate A, so that this bridge can be accurately positioned thereon, and screws 90 46 and 47 are used, passing through the box-like ends of the bridge, to hold the same to the plate. By screwing down on the screws 46 and 47 the top of the bridge 38 may be slightly adjusted relatively to the bottom 95 wing 40, so that end shake on the staff 31 can be adjusted. If desired, the usual top bridge *b'* may be mounted on the top arm 38 and held in place by the usual screws *b'*.

The bridge *b* forms a strong light part in 100 which the barrel and spring can be nicely mounted.

I mount the center staff in a bridge *c*, somewhat similar in construction and which is shown in detail in Figs. 21 and 22. This 105 bridge consists of a top arm 48, which has suitable wings 49, bent down at its left-hand end, as shown. When the bridge is in position on the plate, these wings do not bodily rest upon the plate, but only the outside 110 edges thereof, as shown in Fig. 22. The object of this construction is to provide a strong and box-like support at this end of the bridge, and still a construction which will permit of up-and-down adjustment of the top wing. 115 When the top wing is adjusted down, the side arms will spring slightly outwardly. This operation is shown in Figs. 8 and 10 in connection with another bridge, which will be hereinafter described. This is the operation 120 of all the side arms of the bridges which I will hereinafter describe as having only the points of the side wings resting on the base-plate when the bridge is in position. The other end of the bridge is bent down to form 125 an end part 50 and a bottom part 51. The bearings or jewels for the center staff are formed or mounted in these arms 48 and 51. The bridge also has wings 52 at its right-hand end, which are bent down to solidly rest on the plate. Screws 53 and 54 are passed through the ends of this bridge, as shown, and, if desired, pins 55 may be secured in the plate or base A, so that this bridge can be al-

ways set in the same position. It will be seen that by adjusting the left-hand screw 54 the top arm 48 of this bridge can be adjusted relatively to the bottom arm 51, and thus end 5 shake can be readily adjusted on the center staff.

I find that it is not necessary in practice to make any lateral adjustment between the bridges *b* and *c* to get proper mesh between 10 the barrel-gear and center pinion, as this mesh is comparatively large and can be properly determined by the pins before referred to.

The staff of the center gear is carried through the base in the ordinary manner to 15 carry the minute-hand, the ordinary reducing-gear being placed on the under side of the disk to drive the hour-hand, which is mounted on a quill on said staff in the usual manner, not necessary to describe at length.

20 The bridges *d*, which carry the staves of the third, fourth, and fifth gears, are substantially the same in construction, and a description of one in detail will suffice. The preferred form of this bridge is shown in detail in Figs. 25 12 and 13. The same consists of U-shaped pieces, preferably, though not necessarily, made of one piece of metal, thus forming a top arm 56, an end arm 57, and an under arm 58. In the laterally-extending top and bottom 30 arms the jewels or bearings 580 for the staff are mounted. The bridge is held in place on the base by a screw 59. Mounted on this screw is an eccentric quill 60, which has a head 61. This eccentric quill fits in slots 62, cut in the lateral arms, as shown. The quill is so arranged that the bottom of the same will clear the base A. A pin 63 is secured in the base A, and the same fits in a hole punched in the lower arm, and the top arm rests against this pin. The 40 way this bridge is put on the base-plate is as follows: The staff is put in the lateral arms of the bridge, and then the bridge with this staff is placed on the pin 63. Then by adjusting the eccentric quill 60 the bridge can be swung around the pin laterally to adjust the gearing into proper mesh. When this is 45 done, the screw 59 is used to clamp the device in place. The normal position of the arms relatively to the top of the pin 63 is shown in Fig. 23. When the screw is screwed down to clamp the bridge in its adjusted position, the ends of the two arms 56 and 58 will be brought closer together, as shown in Fig. 50 24, so that the bearings or jewels will tightly engage the ends or shoulders of the staff. To now get the desired proper end shake, the screw is turned down still tighter. This 55 will cause the upper arm 56 to pivot about the top of the pin 63, and thus to relieve the 60 journals or jewels, so that the staff can be set to properly run. Also it will be seen that this adjustment is obtained by setting the screw 59 still tighter, so that the bridge will be very tightly held in place. A modified 65 construction of this bridge is shown in Figs. 14 and 15. In this construction I do away with the eccentric quill and run the screw

through slots 64, cut in the bridge, and these slots are wide enough to permit of lateral play on the pin, so that the proper depthening can 70 be obtained by adjusting the bridge around the pin by hand, and then the screw used to clamp and adjust, as before described. A still further modification is shown in Figs. 16, 17, and 18. In this modification I use side wings 75 65, extending down from the top arm, as shown, the points of which side wings rest on the base A, so that by setting the screw the top arm can be adjusted relatively to the lower arm. The screw in this modification is arranged in 80 a slot cut in the bridge, as shown, but this screw tightly engages the sides of this slot. A slot 67 is cut in the bottom arm, and fitting therein is a small eccentric 68, which is mounted on a shaft with a screw-head 69. Thus by 85 turning this shaft the bridge can be pivoted about the screw 59, and, if desired, the entire bridge can be slid forward and backward endwise by hand on the eccentric and screw. The preferred form of bridge construction, 90 however, is shown in Figs. 12 and 13 or Figs. 14 and 15, and the same constitutes a very simple and efficient bridge, which has a very simple adjustment, and which may be very securely clamped in place, as before described. 95

The staff of the fourth gear is carried through the base in the usual manner, and has the second-hand mounted thereon.

If my improvements are applied to a lever-watch, as shown in Fig. 2, a bridge *d*', similar 100 to the bridges *d* *e*, previously described, is used for mounting the lever.

The balance-wheel staff is mounted in a bridge *g*, as is shown in detail in Figs. 6 to 105 11, inclusive.

g' represents the staff of the balance-wheel. This staff is mounted in bridge *g*, which has a top arm 70, an end arm 71, and a bottom arm 72, and in the laterally-extending arms 70 and 72 the bearings or jewels 700 and 720 110 are arranged. The top arm also may have side wings 73, which extend down to have the points thereof bear on the base A, as shown in Fig. 10. A slot 74 is cut in the lower arm, and fitting into this slot is a pin 115 75, set in the base. A screw 76 is passed through the bridge, and the same carries an eccentric 77, with a head 78, similar to the eccentric shown in Figs. 12 and 13. By means of this eccentric the bridge may be pushed 120 forward and backward about the pin 75, and thus the proper adjustment of the escapement can be obtained, and by adjusting the screw 76 the top arm can be adjusted relatively to the bottom arm to get the proper end shake on the 125 staff *g*'. The top arm also has an extending piece 79, to which the end of the hair-spring can be secured, and the usual bush 80 may be mounted in the top arm and the setting-lever 81 pivoted thereon. Thus it will be seen that 130 I have provided a watch in which the parts are very strongly secured in position and an arrangement by which adjustment can be easily obtained in almost every direction.

The way my watch is preferably set up is as follows: The staves are set in their proper bridges, and the bridges carrying the barrel-gear and center pinion are first set in place 5 and rigidly secured to the base. The bridge carrying the third staff is then secured to the base and the proper mesh obtained, and then the staff adjusted to properly run. The bridges carrying the fourth and fifth staves 10 are then set in place and adjusted in the same manner, and if the watch has a lever-escape-ment the lever is then set and adjusted in the same manner, and the balance-wheel is lastly set in place. With this arrangement a 15 watch can be very accurately and rapidly assembled and adjusted.

As before stated, the bridges and their staves can be made and assembled in large quantities and many of the parts of the watch 20 20 put together before the entire watch is assembled.

While I have shown each bridge as preferably made of one integral piece of metal bent to the desired shape, it is of course 25 within the scope of my invention to make the same up of separate pieces of metal secured together as desired.

I have used the term "bearing or jewel" 30 throughout this specification because the number of jewels that are used in the watch depends upon the quality of the watch, and of course the ends of the staff can be simply set in bearings in the arms of the bridges, or 35 jewels can be set in the arms of the bridges, as desired.

The details and arrangements as herein described may be further carried out by a skilled 40 watchmaker without departing from the scope of my invention as expressed in the claims.

Having thus fully described my invention, what I claim, and desire to secure by Letters Patent, is—

1. A bridge for chronometric construction, 45 comprising end and laterally-extending top and bottom arms, the lateral arms carrying bearings or jewels for a staff, and means for adjusting the bridge bodily to obtain proper deepthing of the gearing, substantially as 50 described.

2. In a chronometric construction, the combination of a base, a bridge comprising end and laterally-extending top and bottom arms

mounted thereon, the lateral arms supporting or carrying a staff, means for adjusting the 55 top arm relatively to the bottom arm to adjust end shake of the staff, and means for adjusting the bridge to obtain proper mesh of the gear, substantially as described.

3. A bridge for chronometric construction, 60 comprising end and laterally-extending top and bottom arms, the lateral arms carrying a staff, and side wings extending down from the top lateral arm, substantially as described.

4. The combination of a base or plate, a 65 bridge mounted thereon and comprising end and laterally-extending top and bottom arms which carry or support the staff, a pin passing through the lower arm, and against which the top arm bears, and a screw bearing on 70 the top arm for clamping the bridge in place, and moving or pivoting the top arm about the top of the pin to adjust the ends of the arm to regulate end shake of the staff carried by the lateral arm, substantially as de- 75 scribed.

5. The combination of a base, a bridge mounted thereon comprising end and laterally-extending top and bottom arms which support the staff, a pin passing through the 80 lower arm, a screw passing through the bridge, and an eccentric quill mounted on the screw, substantially as described.

6. The combination of a base, a bridge mounted thereon comprising end and laterally-extending top and bottom arms which support the staff, a pin secured in the base 85 and passing through the bottom arm and supporting the top arm, a screw passing through the bridge, and an eccentric quill mounted 90 on the screw, substantially as described.

7. A bridge for chronometric construction, comprising end and laterally-extending top and bottom arms, which support or carry the staff, and side wings or arms extending down 95 from the top arm, and so arranged that the points thereof will bear on the base, substantially as described.

In testimony whereof I have hereunto set my hand in the presence of two subscribing 100 witnesses.

DAVID HARRINGTON.
